BOBBIN OR QUILL CLEANING ATTACHMENT FOR LOOMS.

1,312,750.

Specification of Letters Patent.

Patented Aug. 12, 1919.

Application filed February 14, 1917, Serial No. 148,500. Renewed July 29, 1918. Serial No. 247,315.

To all whom it may concern:

Be it known that we, GEORGE H. REDMOND, DAVID R. HARRIMAN, Jr., and OLIVER L. RICHARDSON, citizens of the United States, 5 residing at Griffin, in the county of Spalding and State of Georgia, have invented certain new and useful Improvements in Bobbin or Quill Cleaning Attachments for Looms; and we do hereby declare the following to be a 10 full, clear, and exact description of the invention, such as will enable others skilled in the art to which it appertains to make and use the same.

The invention relates to a loom attachment for cleaning the yarn from bobbins or quills before leaving the loom.

The object of the present invention is to provide a simple, practical and efficient quill or bobbin cleaning attachment of strong, 20 durable and comparatively inexpensive construction adapted to be readily applied to a loom and capable of catching the quill or bobbin as the same is forced out of the shuttle by a full bobbin and of automatically 25 cleaning the bobbin or quill and thereby dispensing with the large cost of labor now required to clean the quills or bobbins by hand, an operation which is very painful to the laborer and also expensive to the 30 manufacturer and also dispensing with separate machines for stripping the bobbins.

Under the construction of looms now in operation the yarn or filling is run down or wound off to a certain point when the loom 35 automatically throws out the quill or bobbin and replaces it with a new or full one. This operation is generally performed by what is known as the filling feeler, and the present invention in its preferred form is 40 applied to the combined feeler and replenishing mechanism and in its preferred form is adapted to automatically extract the quill or bobbin and clean and deliver the same into the can or quill box, which ordinarily 45 receives the uncleaned quills or bobbins.

With these and other objects in view, the invention consists in the certain broad combinations of parts hereinafter fully described, illustrated in the accompanying 50 drawings and pointed out in the claims here-to appended; it being understood that various changes in the form, proportion, size

and minor details of construction, within the scope of the claims, may be resorted to without departing from the spirit or sacrificing any of the advantages of the broader 55 features of the invention.

In the drawings:

Figure 1 is an end elevation of a quill or bobbin cleaning device constructed in accordance with this invention and shown applied to a loom, portions being omitted.

Fig. 2 is a side elevation illustrating the construction of the mechanism for connecting the attachment with the feeler mechanism shaft.

Fig. 3 is a plan view of the attachment.

Fig. 4 is a vertical longitudinal sectional view illustrating the mechanism for forcing the quill or bobbin through the stripping device.

Fig. 5 is an enlarged detail sectional view illustrating the arrangement of the stripping device.

Fig. 6 is a detail sectional view on the line 6—6 of Fig. 4.

Fig. 7 is a detail view of the sectional arm and the rotary lug for actuating the same.

Fig. 8 is a plan view of the sectional arm and the means for moving the pivoted section thereof into the path of the rotary 80 or cam.

Fig. 9 is a detail sectional view on the line 9—9 of Fig. 1.

Fig. 10 is a detail sectional view on the line 10—10 of Fig. 1.

Like numerals of reference designate corresponding parts in the several figures of the drawings.

The drawings illustrate one form or embodiment of the invention, while the claims define the actual scope of the same.

Referring to the drawings 1 designates an approximately L-shaped lever suitably mounted on and depending from the horizontal shaft 2 of the feeler mechanism (not shown), which may be of any well known construction. The arm 1, which is disposed longitudinally of the loom, consists of an upper approximately vertical portion and a lower inclined portion, which is connected by a link or rod 3 with an arm 4 of a shaft or pivot 5 having an upwardly extending arm 6. The arms 4 and 6 and the shaft or

pivot 5 constitute a bell crank, and the said arm 6 is connected by a longitudinal rod 7 with an upper arm 8 of a shaft 9 mounted in suitable bearings of a girt or supporting member 10, on which the said shaft or pivot 5 is also mounted. The girt or supporting member 10, which is arranged at an inclination, is secured at its upper end to the frame of the machine and its lower end is provided with an eye or bearing 11, through which passes the loom shaft 12. The shaft 9, which is disposed perpendicular to the inclined girt or supporting member, is set at a slight inclination and the upper arm 8 is disposed transversely and extends inwardly, as clearly illustrated in Fig. 3 of the drawings, and the said shaft 9 is also equipped at the lower end with an arm or lug 13 arranged to engage a laterally movable outer section 14, which is pivoted to an inner section 15 of a longitudinally disposed inner arm of a transverse shaft 16. The outer arm 14 is connected to the inner arm 15 by a suitable pivot 17 and it is normally maintained in angular relation thereto by a spring 18, as clearly illustrated in Fig. 8 of the drawings. This spring, which may be mounted in any desired manner, is connected with the relatively fixed and movable sections in any desired manner. When the attachment is actuated by the feeler mechanism the inclined arm 1 is moved upwardly a short distance and motion is communicated to the lug or arm 13, which swings the movable section 14 inwardly in alignment with the relatively fixed section and into the path of a rotary lug or cam 19 of the loom shaft 12. The loom shaft 12, in its rotary movement, carries the lug or cam 19 into engagement with the arm and swings the same downwardly partially rotating the shaft 16 and causing an upward movement of an outer arm 20, which is carried by the said transverse shaft 16.

48 The arm 20, which is arranged in substantially horizontal position when the attachment is in its normal position, is provided at its outer end with a slot 21 receiving a pivot, which connects the upper end of a link or rod 22 to the said arm 20 of the transverse shaft 16. The lower end of the link is connected by a suitable pivot 23 with the lower portion of a vertical reciprocating rod or member 24 whose lower end is arranged in a suitable guide 26 and whose upper end carries a stripper 27, and the latter is adapted to receive a quill or bobbin 28 as the same is forced out of the chamber of the shuttle by a full quill or bobbin.

60 The guide 26 is attached to the usual loom rocker-shaft 26' so as to rock therewith in unison with the lay.

The vertical reciprocating guide rod or slidale rod or member 24 has an offset portion to avoid interference with the mecha-

nism of the loom, and its upper end rotatably fits into the depending end of a shank 29 and it is adapted to force the same upwardly against the action of a coiled spring 30. The tubular shank is mounted in a guide 25 and it is provided at its upper end with an enlargement or head 31, to which is pivoted, by a bolt 32 or other suitable fastening device, a pair of jaws 33 constituting the stripping device and normally maintained in and urged toward a closed position by coiled springs 34, which are mounted on the head or enlargement 31 and which are located at opposite sides of the pivot 32. The jaws have upper engaging portions which are provided with inner curved relatively sharp edges 35 adapted to embrace the quill or bobbin for stripping the yarn or other material therefrom. The jaws are provided with upper diverging edges 36 forming a mouth or entrance to the space between the engaging edges 35 and adapted to enable the jaws in the upward movement of the device to engage the quill or bobbin and be spread by the same whereby the device is adapted to seize and hold the same as the bobbin is forced out of the bobbin chamber of the shuttle by a full quill or bobbin. The upper guide 25 is provided with a projection, preferably formed by a screw 37, or other suitable device, which engages a spiral groove 38 and is adapted to produce a rotary movement of the stripping device simultaneously with the upward as well as downward movement thereof whereby the stripping device is adapted to engage the quill or bobbin in the shuttle box and carry the same downwardly and simultaneously rotate the quill or bobbin to turn the same from a transversely disposed position with relation to the loom to a longitudinally disposed position with respect thereto. The lay 40 of the loom is designed to be cut away sufficiently to permit the said upward and downward and rotary movement of the quill or bobbin. The upper guide 25 is preferably in the form of a stripper stand or bracket to enable it to be readily mounted on the loom, as clearly shown in Fig. 5 of the drawings, but the parts may of course be mounted in any other desired manner as will be readily understood. It is located directly beneath the shuttle box to enable the stripper or stripping device to move upwardly into the said shuttle box, as clearly shown in Fig. 5. While a single spiral groove and engaging projection is illustrated in the accompanying drawings, the spiral groove may be duplicated or any equivalent mechanism may be employed for effecting a partial rotary movement of the stripping device.

The movement of the rod or member 24 in an upward direction carries the bobbin or quill stripper up and in position to re-

ceive the quill or bobbin as the same is forced out of the shuttle by the full quill or bobbin. The stripper engages the quill or bobbin with its jaws back of the bunch of 5 unused yarn. This operation being completed, the cam 19 releases lug 14 and permits the parts to return by gravity as well as the action of spring 30 to their normal position. In the reverse movement of the 10 mechanism, the quill or bobbin stripper draws the quill or bobbin down and turns it through the slot or cut away portion 41 of the lay 40. This places the quill in position to be cleaned by the stroke or movement of 15 the lay. The lay not having sufficient stroke to drive the quill or bobbin clear of the yarn, the following mechanism is provided for supplementing the action of the lay. The quill or bobbin now being in position 20 and the lay moving backward the small end of the quill is carried into a centering concavity 42 of a quill pushing head 43 carried by a rod 44, which is mounted to slide in a suitable stationary tubular 25 bracket 45. The concavity guides or centers the quill or bobbin and the said bracket is provided with a central passage 45^a for the reception of said push rod or plunger 44, which is actuated by a cam 47 of the 30 crank shaft 48 of the loom. The cam 47 engages a curved arm 49 pivoted at the lower end at 50^a and presenting a concave edge to the cam and provided with a curved longitudinal slot 50, which receives a laterally 35 projecting pin 51 of the push rod or plunger 46. The push rod co-operates with the lay in forcing the quill or bobbin through the stripping device. The quill is forced out of the stripper and the operation of cleaning 40 the yarn from the quill or bobbin is completed in one stroke or revolution of the loom, placing the quill or bobbin in the can or receptacle usually provided for the same and also depositing the waste or unused 45 yarn in a suitable can or bag (not shown) to be provided for the reception of the waste yarn. The pin 51 extends through a side slot 52 of the guide of the push bar or plunger, and the push rod or plunger is returned 50 to its initial position by a coiled spring 53, which is connected with a lug 54 at the lower end of the arm 49. The spring of the stem or shank of the stripper is compressed during the upward movement of the same so as 55 to produce a rapid downward and turning movement of the stripper in carrying the quill or bobbin out of the shuttle box and in positioning the quill or bobbin to be engaged by the reciprocating member 43.

60 What is claimed is:

1. A bobbin or quill cleaning attachment for looms including a stripping device, means for moving the same in position to receive the quill or bobbin as the same is forced out of the shuttle by a full bobbin,

and means for imparting relative movement to the stripper and the quill or bobbin for cleaning the unused yarn or material from the bobbin.

2. A bobbin or quill cleaning attachment 70 for looms including a stripper provided with relatively movable yieldable engaging jaws adapted to embrace a quill or bobbin and strip the yarn therefrom, mechanism for moving the stripper into position to receive 75 the quill or bobbin from the shuttle when the quill or bobbin is forced out by a full quill or bobbin, and means for imparting relative movement to the stripper and the quill or bobbin to effect a cleaning of the 80 latter.

3. A bobbin or quill cleaning attachment 85 for looms including a stripper, means for mounting the same on the lay of a loom below the shuttle box, mechanism controlled by the feeler mechanism of the loom for moving the stripper into and out of position to receive the quill or bobbin as the same is forced out of the shuttle by a full quill or bobbin, and means for imparting relative 90 movement to the stripper and quill or bobbin to effect a cleaning of the latter automatically.

4. A bobbin or quill cleaning attachment 95 for looms including a stripper, means for mounting the same on the lay of a loom, mechanism controlled by the feeler mechanism of the loom for moving the stripper into and out of position to receive the quill or bobbin as the same is forced out of the 100 shuttle, means for withdrawing the stripper and the bobbin or quill, and means located in the path of the quill or bobbin and co-operating with the movement of the lay for forcing the quill or bobbin through the 105 stripping device.

5. A bobbin or quill cleaning attachment 110 for looms including a stripper, means for mounting the same on the lay of a loom, mechanism controlled by the feeler mechanism of the loom for moving the stripper into and out of position to receive the quill or bobbin as the same is forced out of the shuttle, means for withdrawing the stripper and the bobbin or quill, and means located 115 in the path of the quill or bobbin and co-operating with the movement of the lay or forcing the quill or bobbin through the stripping device, said means including a plunger actuated by the loom and adapted to supplement the action of the lay.

6. A bobbin or quill cleaning attachment 125 for looms including a stripper, means for mounting the same on the lay of a loom, mechanism controlled by the feeler mechanism of the loom for moving the stripper into and out of position to receive the quill or bobbin as the same is forced out of the shuttle, means for withdrawing the stripper and bobbin or quill, and means located in 130

- the path of the quill or bobbin and coöperating with the movement of the lay for forcing the quill or bobbin through the stripping device, said means including a 5 guide having a shuttle or quill plunging or guiding portion, and a reciprocatory member operating in the guide and arranged to supplement the movement of the lay in forcing the quill or bobbin through the stripper.
- 10 7. A bobbin or quill cleaning attachment for looms including a stripper, means for mounting the same on the lay of a loom, mechanism controlled by the feeler mechanism of the loom for moving the stripper into and out of position to receive the quill or bobbin as the same is forced out of the shuttle, means for withdrawing the stripper and the bobbin or quill, means located in the 15 path of the quill or bobbin and coöperating with the movement of the lay for forcing the quill or bobbin through the stripping device, said means including a guide, a reciprocatory member mounted in the guide and arranged to engage the quill or bobbin, an oscillatory arm connected with the reciprocatory member, and a rotary cam actuated by the loom and arranged to engage the said arm.
- 20 8. A bobbin or quill cleaning attachment for looms including a stripper, means for mounting the same on the lay of a loom, mechanism controlled by the feeler mechanism of the loom for moving the stripper into and out of position to receive the quill or bobbin as the same is forced out of the shuttle, means for withdrawing the stripper and the bobbin or quill, means located in the 25 path of the quill or bobbin and coöperating with the movement of the lay for forcing the quill or bobbin through the stripping device, said means including a reciprocatory member mounted in the guide and arranged to engage the quill or bobbin, an oscillatory arm connected with the reciprocatory member, and a rotary cam actuated by the loom and arranged to engage the said arm.
- 30 9. A bobbin or quill cleaning attachment for looms including a stripper, means for mounting the same on the lay of a loom, mechanism controlled by the feeler mechanism of the loom for moving the stripper into and out of position to receive the quill or bobbin as the same is forced out of the shuttle, means for withdrawing the stripper and the bobbin or quill, means located in the 35 path of the quill or bobbin and coöperating with the movement of the lay for forcing the quill or bobbin through the stripping device, said means including a reciprocatory member arranged to engage the quill or bobbin to supplement the action of the lay, and a cam operated by the loom for actuating the said reciprocatory member.
- 40 10. A bobbin or quill cleaning attachment for looms including a stripper, means for mounting the same below the shuttle box, means for moving the same upwardly and downwardly into and out of the shuttle box and for partially rotating the stripper to turn the quill or bobbin after the same is removed from the shuttle box, and means 45 located in the path of the quill or bobbin for forcing the same through the stripper, and means controlled by the feeler mechanism of the loom for throwing the stripper actuating mechanism into operation.
- 50 11. A bobbin or quill cleaning attachment for looms including a stripper, means for mounting the same below the shuttle box, means for moving the same upwardly and downwardly into and out of the shuttle box and for partially rotating the stripper to turn the quill or bobbin after the same is removed from the shuttle box, and means 55 located in the path of the quill or bobbin for forcing the same through the stripper, and means controlled by the feeler mechanism of the loom for throwing the stripper actuating mechanism into operation.
- 60 12. A bobbin or quill cleaning attachment for looms including a stripper, means for mounting the same below the shuttle box, means for moving the same upwardly and downwardly into and out of the shuttle box and for partially rotating the stripper to turn the quill or bobbin after the same is removed from the shuttle box, and means 65 located in the path of the quill or bobbin for forcing the same through the stripper, and means controlled by the feeler mechanism of the loom for throwing the stripper actuating mechanism into operation.

turn the quill or bobbin after the same is removed from the shuttle box, means located in the path of the quill or bobbin for forcing the same through the stripper, and means controlled by the feeler mechanism of the loom for throwing the stripper actuating mechanism into operation, said means including an arm connected with the feeler mechanism shaft, a rotary element connected with the loom, an arm or lever having a movable section normally located out of the path of the said rotary element of the loom, and means actuated by the arm of the feeler mechanism shaft for moving the said movable portion of the arm or lever into the path of the rotary element of the loom.

13. A bobbin or quill cleaning attachment for looms including a stripper, means for mounting the same below the shuttle box, means for moving the same upwardly and downwardly into and out of the shuttle box and for partially rotating the stripper to turn the quill or bobbin after the same is removed from the shuttle box, means located in the path of the quill or bobbin for forcing the same through the stripper, and means controlled by the feeler mechanism of the loom for throwing the stripper actuating mechanism into operation, said means comprising an arm connected with the feeler mechanism shaft, a rotary cam actuated by the loom, an arm or lever having a pivoted spring actuated section normally located out of the path of the cam, a rock shaft arranged to move the movable section of the arm or lever into the path of the cam, and means for transmitting motion from the arm of the feeler mechanism shaft to the rock shaft.

14. A bobbin or quill cleaning attachment for looms including a stripper, means for mounting the stripper beneath the shuttle box of the loom, means for moving it upwardly and downwardly to carry it into and out of the shuttle box, said means being controlled by the feeler mechanism, and means for automatically rotating the stripper during such upward and downward movement and for producing a quick rotary movement when the stripper is carried downwardly.

15. A bobbin or quill cleaning attachment for looms including a stripper, means for mounting the stripper below the shuttle box of a loom for vertical movement, means for imparting a partial rotary movement to the stripper when the same is moved upwardly and downwardly, a transverse shaft having an arm connected with the stripper for moving the same upwardly and downwardly, an arm or lever having a movable section, a rotary cam actuated by the loom, and mechanism controlled by the feeler mechanism of the loom for moving the said movable section into the path of the cam for causing the latter to actuate the stripper.

14. The combination with a loom, of a stripper mounted on the lay and adapted to engage the quill, and means coöperating with the quill during the movement of the lay to thus cause the stripper to function.
15. The combination with a loom, of a stripper mounted on the lay and adapted to engage the quill, and means coöperating with the quill during the movement of the lay to thus cause the stripper to function, said means embodying a reciprocable member and means for reciprocating it in the opposite direction to the movement of the lay during the stripping action.
16. The combination with a loom, of a stripper mounted on the lay and adapted to engage and hold the quill as the quill is discharged from the shuttle by the replenishing mechanism, devices whereby the quill may be rötated to a position at right angles to the shuttle-race, and devices co-acting with the quill for causing the stripper to function while in such position.
17. The combination with a loom, of a stripper mounted on the lay of the loom in position to receive the quill ejected from the shuttle, means for automatically causing a relative movement of the stripper and the quill during the operation of the lay to thereby strip the quill without stopping the operation of the lay.
18. The combination with a loom, of a stripper positioned to receive and hold the quill as the same is ejected from the shuttle,
- means co-acting with the stripper whereby the subsequent operation of the loom performs a stripping operation, said means embodying a reciprocating member adapted to engage the end of the quill and assist in causing endwise movement of the quill with respect to the stripper.
19. The combination with a power loom, of a stripper mounted on the lay, means automatically operated from the combined feeler and replenishing mechanism for positioning the stripper to receive the ejected quill, and devices automatically operated by the loom mechanism for causing the relative movement of the stripper and the quill to perform the stripping function.
20. The combination with a power loom, of a stripper mounted on the lay adapted to receive the ejected quill and position it parallel to the sides of the lay, means for rotating the stripper to swing the quill to an angular position with respect to the lay, and means engaging the quill and coöperating with the stripper whereby the movement of the lay causes the stripping of the quill.

In testimony whereof we affix our signatures in presence of two witnesses.
